STATIC ELIMINATING METHOD AND
APPARATUS

Harry L. Moir, Chicago, Ill.

Application May 20, 1938, Serial No. 209,131

2 Claims. (Cl. 178—44)

This invention relates to static eliminating method and apparatus, and more particularly to improved means for reducing interference during the reception of a note of a fixed audio frequency.

One feature of this invention is that it substantially completely eliminates from the output of a radio receiver all undesired interference created by static and the like, during reception of a radio wave modulated by a fixed audio frequency wave or note; another feature of this invention is that it enables the signal to noise level ratio to be greatly increased in connection with reception of continuous wave telegraphy and radio direction finding signals; other features and advantages of this invention will be apparent from the following specification and the drawing, in which:

Figure 1 is an illustrative diagram, partly in circuit form, of one embodiment of my invention; and Figure 2 is a schematic diagram of a modification of my invention.

There are certain forms of communication and radio reception wherein it is only necessary to reproduce in the loud speaker or other translating device an audio wave of a given note, which note may be of a fixed and predetermined frequency. This is true, for example, in continuous wave telegraphy, where the aerial of the transmitter is energized with a continuous carrier wave, modulated at intervals with an audio note or wave of a fixed frequency. In the reception of such a signal the audio note is separated from the carrier, as by a conventional detector unit, and it is this fixed audio wave which is amplified in the audio amplifier and delivered to the output of the receiver. Another important commercial use of an audio wave of fixed frequency is in the sending of signals for radio direction finding. The signal transmitted in this work is in many respects similar to continuous wave telegraphy, a carrier being modulated at intervals by a fixed audio note, except that the modulation sequence is generally repeated in a fixed pattern.

In the reception of such signals it has been customary to use a radio receiver which is responsive throughout to a band of frequencies, this being the conventional receiver adapted to also receive broadcast or phone signals. Such a receiver has a tuned radio frequency or an intermediate frequency portion adapted to pass a band several thousand cycles wide, and the audio frequency portion is generally uniformly responsive, or substantially so, to frequencies from about fifty to five thousand cycles per second. Regardless of how sharp the tuning of the radio frequency portion may be in such a receiver, noise

or undesired static impulses inevitably pass through the receiver with the signal, and are reproduced in the speaker or ear phones.

The present invention provides means for receiving signals comprising a fixed audio frequency wave in such a manner as to reproduce in the translating device only such audio wave, and substantially none of the undesired interfering impulses which have passed through the radio frequency portion of the receiver with the signal. 10 This is accomplished by using, in the audio frequency portion of the receiver, a crystal or other vibratory element very sharply tuned to the frequency of the signal, so that undesired impulses having an effective frequency of only a very few 15 cycles difference from the desired signal wave are eliminated from the output of the receiver.

In the particular embodiment of my invention illustrated in Figure 1, only the basic elements of a radio receiver are illustrated, it being understood that my invention is applicable to receivers of the more complex modern type, and, in fact, to any type. In the illustrative figure an antenna system 10 is adapted to receive radio waves, and particularly those of the type comprising a 25 carrier modulated with a fixed audio wave, and to deliver them to a radio frequency amplifier 11 of conventional type, which would also include tuning means. The output of the radio frequency amplifying portion of the receiver is 30 transmitted to a detector portion 12, here shown as separate for purposes of convenience in illustration. The output of the detector portion 12, comprising the desired signal of a fixed audio wave and other undesired interfering impulses, 35 would then be delivered to the audio frequency amplifying portion of the receiver, here shown as being coupled thereto by the transformer 13. The output of the transformer 13 is here shown as developed across the grid 14 and cathode 15 40 of a tube 16, which tube may be self-biased by the resistor 17. The output of the tube 16, or first audio stage, is delivered by the plate 18 to the primary of the transformer 19. The secondary of this transformer develops a voltage 45 differential between the grid 20 and cathode 21 of the second amplifying tube 22; but the voltage differential developed between these two elements is controlled by filter means 23 comprising an 50 element adapted to vibrate mechanically at a definite frequency.

This vibratory element is here illustrated as a piezoelectric crystal 24, preferably of Rochelle salt, in electrical contact with two elements, such 55

as metal foil, 25 and 26, through which the circuit is completed.

In the position shown in Figure 1, the vibratory element acts as a filter, passing to the grid of the tube 22 only those voltages which have a frequency substantially conforming to the frequency of mechanical resonance of the vibratory element. This element must, of course, be so designed as to have a very sharp frequency characteristic curve. Quartz crystals used in radio frequency portions of receivers generally pass a band several thousand cycles wide; the vibratory element 23, however, should be so sharply peaked that if its period of mechanical resonance is 1450 cycles per second, the energy passed thereby should be in the neighborhood of five times or more down at five cycles off of this frequency, on either side. The frequency of mechanical resonance of the crystal is not here spoken of as the "natural" frequency of vibration, since a crystal allowed to vibrate without restraint generally passes too wide a band for the purposes of this invention; and the "natural" frequency of a crystal of convenient size may not be within the audio band. It is necessary, in order to have a crystal peaked very sharply at a frequency within the audio range, to mechanically or otherwise constrain it to damp out the vibration, this damping resulting in vibration substantially only at the desired fixed frequency. This damping may be conveniently accomplished, for example, by mass loading of the crystal.

The output of the tube 22 is here shown as delivered from the plate 27 thereof to a coupling transformer 28 which effects delivery of the output to a translating device 29, here shown as a loud speaker. As a result of the filtering action of the vibratory element 23 substantially only the desired signal wave is reproduced in the loud speaker. If all of the undesired impulses were of wave form of a definite frequency there would be no audible interference; but because of the steep wave fronts of some of the static impulses shock excitation may still result in a few undesired impulses in the speaker. The proportion of these undesired impulses, however, is only a very few percent of those which would otherwise be present in the speaker; and the signal to noise ratio is greatly raised, frequently ten to twenty times over the ratio existing without the use of this invention.

In the modification of my invention illustrated in Figure 2 an antenna system 31 delivers signals to a radio frequency amplifier 32, a detector unit 33, and an audio amplifier 34, these various portions of the receiver being arranged in cascade as shown. In this modification of my invention, however, two vibratory elements, here shown diagrammatically as 35 and 36, are used, here being

placed immediately prior to the translating device or speaker 37, one being placed in each of the leads thereto. While these vibratory elements are here shown for illustrative purposes as outside of the audio amplifying portion of the receiver it should be understood that as a practical matter they would be incorporated therein. The use of two vibratory elements, one in the return circuit for the other, has been found to result in improved operation, even fewer undesired impulses getting through to the translating device.

Because of the fact that the vibratory elements are generally damped or physically constrained in order to sharpen their frequency-response characteristic curve, it is preferable to place at least one or more stages of audio amplification ahead of the vibratory element. In Fig. 1, for example, the vibratory element 23 is shown in use after the first stage of audio amplification; and in Figure 2 the vibratory elements 35 and 36 are shown in use following the last stage of a several-stage audio amplifier. An arrangement of the type illustrated in Figure 1, wherein the vibratory element is followed by at least one stage of audio amplification, is preferable if a large output is desired, since such a large output might overload the elements when used in the position shown in Figure 2.

While I have described certain embodiments of my invention, it is to be understood that it is capable of many modifications. Changes, therefore, in the construction and arrangement may be made without departing from the spirit and scope of the invention as disclosed in the appended claims in which it is my intention to claim all novelty inherent in my invention as broadly as permissible in view of the prior art.

I claim:

1. Apparatus of the character described for reducing undesired interfering impulses during reception of a radio carrier wave modulated by audio frequency components including a wave of fixed frequency, including: a receiver comprising a radio frequency portion, a detector portion, an audio amplifier portion; and a mass-loaded piezo-electric crystal in said audio amplifier portion controlling the passage of waves therethrough, said crystal having a frequency of mechanical vibration the same as that of said wave of fixed frequency, whereby substantially only said last mentioned wave is delivered to the output of said receiver.

2. Apparatus of the character claimed in claim 1, wherein there are two of said crystals in said audio amplifier portion, one being in the return portion of the circuit containing the other.

HARRY L. MOIR.
